DESIGN FOR A FLUID DISPENSING DEVICE

John C. Cox, St. Louis, Mo., assignor to Wagner Electric Corporation, St. Louis, Mo., a corporation of Delaware

Application May 4, 1939, Serial No. 84,781

Term of patent 14 years

To all whom it may concern:

Be it known that I, John C. Cox, citizen of the United States of America, residing at the city of St. Louis, State of Missouri, have invented a new, original, and ornamental Design for Fluid Dispensing Devices, of which the following is a specification, reference being had to the accompanying drawing, forming a part thereof.

In the drawing Figure 1 is a side elevation; Figure 2 is a top plan view; Figure 3 is a bottom plan view; and Figure 4 is a fragmentary enlarged section taken on the line 4—4 of Figure 3.

I claim:

The ornamental design for a fluid dispensing device, as shown.
